E. D. TALBOTT

COSTUME PROTECTOR FOR DISPLAY HANGERS

Filed May 15, 1926

UNITED STATES PATENT OFFICE.

EMELINE D. TALBOTT, OF ALEXANDRIA, VIRGINIA.

COSTUME PROTECTOR FOR DISPLAY HANGERS.

Application filed May 15, 1926. Serial No. 109,450.

The invention relates to new and useful improvements in costume protectors for display hangers.

An object of the invention is to provide 5 a costume protector for display hangers which includes a covering adapted to be attached to the hook for the hanger and overlie the costume on the support of the hanger, which costume protector is provided with a 10 front and rear curtain, and wherein the front curtain is so constructed that it may be folded back on the shoulder portions of the protector so as to display the neck portion of the costume.

15 A further object of the invention is to provide a costume protector of the above type which is so constructed that the front and back curtains are supported by an intermediate portion extending from one 20 shoulder to the other so as to avoid pinching or crushing the costume during storing and during display.

25 A still further object of the invention is to provide a costume protector of the above type wherein the front curtain is divided in such a way as to completely cover the costume beneath the protector when folded down into protecting position, and which may be readily folded back to display the 30 neck portion of the costume.

These and other objects will in part be obvious and will in part be hereinafter more fully disclosed.

35 In the drawings which show by way of illustration one embodiment of the invention—

40 Figure 1 is a front view of my improved costume protector and showing in broken lines the front portion of the protector folded back to display the neck of the costume;

45 Fig. 2 is a sectional view on the line 2—2 of Fig. 1, and

Fig. 3 is a perspective view of a portion 50 of the protector with the sections of the front curtain turned away from each other.

The invention broadly is directed to a 55 protector for costumes which are hung on display forms whereby they may be readily stored. The hanger is of the usual type consisting of a curved bar and a central supporting hook. The protector is made of fabric or some other material which is equally as pliable. In the preferred form of the invention, the protector includes a

central strip which extends from the tip of one shoulder of the hanger to the tip of the other shoulder. Attached to this central section, is a rear curtain and also sections forming a front curtain. The rear curtain 60 is shaped at its upper edge to conform to the curvature of the hanger, and is secured to the central section preferably by stitches. The central section has a hole therethrough intermediate its ends and sides, through 65 which the hook of the hanger can be passed, so that the protector is thus secured to the hanger. The front curtain of the protector is made in two sections which overlap in the central part of the hanger. These sections are curved at their upper edges and 70 are secured to the central section of the protector, preferably by stitching. The overlapped portions of the front curtain are preferably provided with a snap fastener at 75 the lower ends thereof, so that they may be joined together to hold the protector closed, and thus the costume well protected which is 80 on the hanger. These sections may be separated from each other and folded back on to the shoulder portions of the costume for displaying the neck of the costume.

Referring more in detail to the drawings, the costume hanger as illustrated consists of a bar 1 preferably of wood so that it is light. 85 This bar is curved from one end to the other. Centrally of the bar is a hook 2 which is of the usual type. The costume is placed on this hanger in the usual way. In the drawings, I have illustrated a costume at 3. 90 This improved protector for costume is especially adapted for protecting ladies' costumes, and particularly evening gowns.

The protector consists of a central portion 4 which extends from the point 5 to the 95 point 6 in Fig. 1 of the drawings. This central portion is provided with a hole 7 which may be reinforced by stitching, or by metal, or in any other suitable way. The hole is located centrally between the ends of 100 the central section, and centrally between the side edges of said central portion. Secured to this central portion is a rear curtain 8. This rear curtain 8 is curved along its upper edge 9 to conform to the shaping 105 of the rod 1 of the hanger. The rear curtain is secured to the central portion 4 by a line of stitching 10, and this line of stitching extends from the point 5 to the point 6 in Fig. 1, so that the rear portion of the pro- 110

ector is completely closed all along its upper edge.

Secured to the central portion 4 is a front curtain consisting of two sections 11 and 12. The upper edges of these two sections are curved as indicated at 13 in Figures 1 and 3. The upper edge of these sections of the front curtain is secured to the central portion 4 by a line of stitching 14. The two sections are stitched to the central section in such a way that their adjacent vertical edge portions overlap. The under edge portion is indicated at 15 in Fig. 3, and the outer edge portions is indicated at 16. Otherwise, the entire upper edge of the front curtain is closed. By overlapping these adjacent vertical edge portions of the two front sections 11 and 12, the sections will hang so as to completely close and conceal and protect the costume underneath the same. In order to hold these sections in closed position, I have provided a snap fastener 17, which is of the usual construction. The costume 3 is placed on the hanger after which the protector is let down over the same, and the front sections of the front curtain closed. The hanger can then be stored in the usual manner. When it is desired to display the garment, the saleslady will grasp the protector at one side of the hook and lift the hanger from the support. The hand of the saleslady does not come in contact with the costume in any way whatever. The protector being made of a pliable material such as fabric, will permit the parts beneath the protector to be firmly gripped for holding the hanger while showing the costume. After lifting the hanger from its storage place, then the saleslady holds the hanger by the hook, and by releasing the snap joining the front sections of the curtain, said front sections may be folded back on to the shoulder portions of the costume as indicated in broken lines in Fig. 1, and in full lines in Fig. 3. This folding back of the sections of the front curtain, brings to view the neck portion of the costume. This can be accomplished without raising the protector from the costume in any way.

By providing the protector with the central section, the curtains are connected in such a way that they are separated from each other at their upper edges, and therefore, hang in spaced vertical planes. This prevents the protector from pinching or

crushing the parts of the costume directly beneath the same. 55

It is obvious that minor changes may be made in the details of construction without departing from the spirit of the invention as set forth in the appended claims. 60

Having thus described the invention, what I claim as new and desire to secure by Letters-Patent, is—

1. A costume protector for display hangers comprising a covering of fabric adapted to be placed over the costume supported on the hanger, said fabric covering being shaped at the upper portion thereof to conform to the curvature of the costume on the hanger, and having front and rear curtains, 70 means for connecting said curtains together in the region of and throughout the entire extent of the hanger, said covering having an opening therethrough for the hook of the hanger, said front curtain having a vertical opening from a point adjacent the hook opening to the bottom thereof, whereby said front curtain can be folded back on the shoulders of the costume on the hanger for displaying the neck portion of the costume. 75

2. A costume protector for display hangers comprising a covering of fabric adapted to be placed over a costume supported on the hanger, said fabric covering being shaped to conform to the curvature of the costume 80 on the hanger and including a central portion extending from one side of the protector to the other side thereof directly over said hanger, said central portion having an opening intermediate its ends and intermediate 85 its side edges for the hook of the hanger, a rear curtain having its upper edge shaped to conform to the hanger and secured to one side edge of said central portion, a sectional front curtain having its upper edge curved to conform to the hanger and secured to the other edge of said central section, the sections of said last-named curtain being constructed so as to meet and overlap centrally 90 of the protector, and means for detachably securing the overlapped portions of the protector together so that said sections may be disconnected and folded back on the shoulders of the costume on the hanger for displaying the neck portion of the costume. 95 100

In testimony whereof, I affix my signature.

EMELINE D. TALBOTT.
